INVENTOR.

John H. Rigby
By his Attorney,
Nelson M. Farwell

UNITED STATES PATENT OFFICE.

JOHN H. RIGBY, OF BEVERLY, MASSACHUSETTS, ASSIGNOR TO UNITED SHOE MACHINERY CORPORATION, OF PATERSON, NEW JERSEY, A CORPORATION OF NEW JERSEY.

SOLE-EDGE-FINISHING MACHINE.

Application filed April 24, 1919. Serial No. 292,321.

To all whom it may concern:

Be it known that I, JOHN H. RIGBY, a citizen of the United States, residing at Beverly, in the county of Essex and State of 5 Massachusetts, have invented certain Improvements in Sole-Edge-Finishing Machines, of which the following description, in connection with the accompanying drawings, is a specification, like reference characters on the drawings indicating like parts in the several figures.

This invention relates to edge setting machines of that type in which an iron for setting the sole edge is vibrated backwardly 15 and forwardly along the length of the sole edge, and in which an indenting wheel is mounted adjacent to the edge setting iron in position to operate upon the upper surface of the welt or similar substance, or sole.

Heretofore it has been proposed to mount 20 the indenting wheel in various ways so that it might move relatively to the edge setting iron, against the action of a spring, to adapt the wheel for indenting welts or sole margins of different widths. None of these 25 structures has enabled any provision to be made for conveniently adjusting the wheel toward and from the surface to be operated upon so as to readily accommodate soles of 30 different thickness.

An important feature of the present invention consists in provision for relative vertical adjustment of edge iron and indenting wheel without disturbing the angular relation 35 between them.

Another important feature of this invention is a combined edge setting and indenting device which permits the indenting device to yield in the direction of its axis of 40 rotation, means being also provided for adjusting the wheel in a direction substantially perpendicular to its axis of rotation.

Another feature of the invention comprises a bodily movable indenting wheel 45 which can be manually swung aside from its normal position to facilitate the removal of one iron and the substitution of another iron for it.

In the illustrated embodiment of the invention, the indenting wheel is so mounted 50 that it will follow the contour of the upper back, by its last, irrespective of the contour of the sole, while being carried by a

swinging support which can be readily manually adjusted to permit the machine to 55 be used for operating upon soles of varying thicknesses.

It has been proposed to mount an edge setting iron for permissive movement about a horizontal axis in order to cause the tool 60 to follow a sole edge of varying relation to the vertical caused, for example, by careless edge trimming. The present invention provides an independent mounting for the indenting wheel so that such movement of the 65 iron does not vary the distance relation between the indenting wheel and the sole edge.

To facilitate the employment of an edge finishing machine for different grades or kinds of work, it is customary to mount the 70 setting tool or iron so that it can be replaced by a different one. Another object of my invention is to enable the change to be made quickly. In the machine illustrated to exemplify the invention, the tool or iron is so 75 mounted that although it is held securely in operative position, it can be ejected from its holder by a manual operation, such ejection being, preferably, preceded by a displacement of the indenting wheel.

Other features of my invention will become apparent as hereinafter described.

In the accompanying drawings, the invention is illustrated in connection with a machine of the type described in United 85 States Letters Patent No. 1,078,684, granted Nov. 18, 1913, but it is to be understood that I do not limit myself to the use of my improvements in connection with that particular type of machine.

In the drawings,

Fig. 1 is a side elevation of a portion of a machine of the type illustrated in the patent above referred to, said machine being equipped with my improved edge setting 95 and indenting devices.

Fig. 2 is a side elevation of the devices which include my present improvements.

Figs. 3 and 4 are perspective views, respectively illustrating the tool holder and the 100 tool separated from each other but in position to be assembled.

When my improvements are embodied in a machine of the type indicated in Fig. 1, the work to be operated upon is clamped in 105 a jack or work support 12 (Fig. 1) carried

by a vertical post in a frame member 13 and so mounted that it may have universal movement in a horizontal plane. A block 14 supports the tread face of the shoe sole and a rest 15 supports the tread face of the heel. A U-shaped clamp 16 engages the counter part of the shoe and a clamp 17 is carried by a plunger 18 which is operated by a handle 19 pivoted at 20.

10 The mounting for the edge setting tool 21 (Figs. 2, 3 and 4) comprises a tool holder 22 having a shank 23 slidably positioned in a member which is oscillated in an extension 24 (Fig. 1) from a sleeve 25 that is rotatably mounted in a bearing frame 26 which is connected by pivots 27 to two pairs of twin levers 28, 29. One pair of levers 28 is pivoted directly upon a lever 30, while the other pair of levers 29 is connected to the lever 30 through a bell-crank 31, the latter being connected with the frame of the machine by an anchor link 32. By this construction, the tool holder can be moved laterally toward and from the work. For a 25 further understanding of the motions imparted to the sleeve 25, frame 26 and the parts carried thereby, reference may be had to the Patent 1,078,684. As stated above, however, I do not limit myself to machines 30 of this particular type, but it is to be understood that, whatever the type of machine may be, the shank 23 and the holder 22 and all parts carried thereby are vibrated as usual along the length of the sole edge.

35 Referring now particularly to Figs. 2, 3 and 4 which illustrate the particular features of my invention, the bracket-shaped holder 22 is formed or provided at its upper end with an ear 33, said bracket-shaped holder 40 being slotted or recessed and the two members thereof provided with vertical ways 34 in which an L-shaped block 35 is fitted to slide. Rising from the upper portion of the block 35 is a threaded pin 36, said pin passing through the ear 33 and provided with nuts 37 by means of which the block 35 can be raised and lowered in the ways 34. Pivotally connected at 38 to the angle portion of the block 35 is an arm 39 by which the stitch 45 indenting wheel 40 is supported in a swinging manner, said wheel being connected to a carrier 41 pivoted at 42 to the lower end of the arm 39. The carrier 41 is pivotally connected at 43 to the lower end of lever 44 carried 50 by a rockshaft 45 mounted in the end of the lower member of the L-shaped block 35. The lower arm of the lever 44 is by preference parallel to, and of the same length as, the arm 39 so that the carrier can be swung 55 without changing the inclination of the wheel axis. The lever 44 is integral with or secured to the rockshaft 45 one end of which projects through a slot 65 in one of the cheek pieces of the holder 22. The upper end of 60 the lever 44 has a slot 46 which receives a

pin 47 projecting from the upper end of the lever 48 pivoted at 49 to the holder 22. The end of the rockshaft 45 which projects through the slot 65 has secured thereto an arm 50 provided with a thumb piece 51 the purpose of which will be hereinafter explained.

70 The reason for the slot and pin connection 46, 47 is to ensure permanent connection between the levers 44 and 48 throughout all 75 vertical adjustments of the wheel carrying block 35.

80 The lower end of the lever 48 has a forwardly projecting and preferably rounded tip 52. Bearing against the back of the lower end of the lever 48 is a sliding pin or 85 plunger 53 which is slotted for a pin 54 mounted in the holder 22 and projecting into said slot to limit the forward and back movements of the pin 53. The pin 53 is normally projected from its socket in the shaft 23 by means of a spring 55.

90 When a piece of work is introduced to substantially the position indicated in Fig. 2, the edge of the sole is pressed against the laterally vibrating tool 21 and shifted along in the usual manner, the upper surface of the sole or the welt being pressed against the indenting wheel 40. The shoe upper bears 95 against the base of the wheel 40 and presses it back against the action of spring 55 transmitted through the lever 48, the lever 44 and the member 41. In this manner the wheel 40 is not only adjustably supported but is also yieldingly supported so that it 100 may move in and out relatively to the margin of the shoe sole so as to automatically accommodate itself to the varying widths of the shoe welt or corresponding part. The outer limit of movement or swing of the wheel 40 is determined by the inner end of the slot in the pin 53 bearing against the limiting pin 54. That is, when the spring 105 55 acts upon the pin 53 so as to swing the lower end of lever 48 to the left from the position in Fig. 2 as far as the slot in the pin 53 will permit, the intermediate connecting lever 44 will transmit that amount of movement and no more to the wheel 40. Consequently, when there is no work in 110 place, the wheel 40 can not be swung so far out as to be out of position to be swung back again when the work is placed in position for edge finishing and indenting.

115 The lever 48 also serves as a means for ejecting the tool 21 from position. The tool 21 is secured to a block 56 having a heel or cam portion 57, by suitable means such as screw 58. The tool 21 has angular recesses 59 which engage the fulcrum edges 60 of the holder 22 to permit rotation about a horizontal axis to fit the vertical face of the sole edge at all times. Said holder is provided, on the inner walls of its cheek pieces, 120 with ledges 61, one of said ledges being cut 125

away or recessed as at 62. When the tool 21 and its block 56, as shown in Fig. 4, are inserted to position in the holder 22 (Fig. 3), the block 56 is passed between the cheek 5 pieces of the holder below the ledges 61 and the upper portion of the tool 21 is pushed in above the ledges 61 until the side lug 63 of the tool drops into the recess 62. The parts are so proportioned that at this time the 10 fulcrum edges 60 of the holder 22 fit the angular recesses 59 of the tool.

The slot 64 formed in one of the cheek pieces of the holder 22, which slot is formed when the ledge 61 is cut away to form the 15 recess 62, enables a tool to be inserted under the lug 63 to lift the latter up if the tool should be stuck and it is desired to remove it. Ordinarily, however, the tool is easily ejected in the following manner:—

20 By pressing against the finger piece 51, the shaft 45 is rocked and the lever 44 is swung so as to transmit swinging motion to the arm 39, thereby swinging the indenting wheel 40 away and up from the position 25 shown in Fig. 2, it being assumed, of course, that at this time there is no work in place. The first portion of this movement carries the wheel 40 some little distance away from the tool 21. During continued actuation of 30 the rockshaft arm 50 by means of the thumb piece 51 the lever 48, owing to the slot and pin connection 46, 47 with the lever 44, is actuated so that the tip 52 at the lower end of the lever 48 contacts with the cam portion 35 57 of the tool block 56 and lifts the rear end thereof up until the lug 63 clears the recess 62, and then a slight further movement throws the tool or iron away from the supporting ledges to enable a new tool to be 40 quickly substituted for the one removed.

Having described my invention, what I claim is:—

1. In an edge setting machine, a holder, an edge finishing iron and an indenting wheel 45 carried thereby, and means for adjusting the wheel perpendicularly to the plane of a shoe sole to position it for soles of different thicknesses.

2. In an edge setting machine, a holder, 50 an edge finishing iron carried thereby, an indenting wheel yieldingly supported by the holder, and means for adjusting the wheel relatively to the plane of a shoe sole, while preserving the angular relation between 55 them.

3. A machine of the class described having, in combination, a holder, an edge iron, an indenting member, a swinging carrier therefor, and parallel connections between 60 the holder and the carrier constructed and arranged to maintain constant the angular relation of the indenting member to the plane of a shoe sole.

4. In a machine of the class described, a holder, a vertically adjustable non-rotary

block carried by said holder, and an indenting wheel having a swinging connection with said block.

5. In an edge setting machine, a holder, an iron loosely carried thereby, a bodily movable indenting wheel, a manually operable member, and connections whereby operation of said member will shift the wheel away from normal position and eject the iron from its holder. 75

6. In an edge setting machine, a holder, an iron loosely carried thereby, a bodily movable indenting wheel, and means for manually shifting the wheel away from normal position and ejecting the iron from 80 the holder.

7. In a machine of the class described, a holder, an indenting wheel having a vertically adjustable connection with the holder, and means for manually displacing the 85 wheel from operative position.

8. In a machine of the class described, a holder, a vertically adjustable member carried by said holder, said member having a rockshaft, an indenting wheel having a 90 swinging connection with said adjustable member, means for manually rocking said shaft, and connections for transmitting motion from said rockshaft to the swinging wheel. 95

9. In a machine of the class described, a holder, a swinging carrier, an indenting wheel supported by the carrier, parallel connections between the carrier and the holder constructed and arranged to maintain 100 constant the inclination of the wheel axis, and means for swinging said carrier to enable the indenting wheel to follow the contour of a shoe upper while engaging the entire margin of the shoe sole. 105

10. In an edge setting machine, a holder, an edge setting iron removably mounted in said holder, means for normally retaining the iron in operative position, and means for manually releasing and ejecting the iron. 110

11. In an edge setting machine, a holder having supporting ledges, an iron removably mounted on said ledges, means for normally retaining the iron in operative position, and means for manually releasing 115 the iron and ejecting it.

12. In an edge setting machine, a holder, a setting tool removably mounted on said holder, said tool having a cam surface, and a manually operable member adapted to 120 contact with said cam surface to eject the tool.

13. In an edge setting machine, an edge setting iron pivotally mounted for movement about a horizontal axis to permit the tool to fit a sole edge of varying angularity to the vertical and an indenting wheel mounted independently of said iron. 125

14. In an edge setting machine, an edge setting iron pivotally mounted for move- 130

ment about a horizontal axis to permit the tool to fit a sole edge of varying angularity to the vertical and an indenting wheel mounted independently of said iron, and 5 maintaining a substantially constant angle with the vertical.

15. In an edge setting machine, a tool carrier, an edge iron and an indenting tool mounted thereon, and means for relatively 10 adjusting the indenting tool and iron vertically while preserving the angular relation between them.

16. In an edge setting machine, a tool carrier, an edge iron and an indenting tool

mounted thereon, and means for adjusting 15 the indenting tool vertically while preserving its angular relation to the edge iron.

17. In a machine of the class described, a holder, an edge iron mounted loosely on the holder to permit the iron to conform to the 20 varying slant of the edge of a shoe sole, and an indenting member mounted to move bodily over the upper margin of the shoe sole to conform to variations in the width of said margin.

In testimony whereof I have signed my name to this specification.

JOHN H. RIGBY.
